LIGHTING BRACKET

Filed May 20, 1926

UNITED STATES PATENT OFFICE

JACOB DYM, OF PITTSBURGH, PENNSYLVANIA, ASSIGNOR, BY MESNE ASSIGNMENTS,
TO PORCELIER MANUFACTURING COMPANY, OF PITTSBURGH, PENNSYLVANIA, A
CORPORATION

LIGHTING BRACKET

Application filed May 20, 1926. Serial No. 110,383.

My invention relates to porcelain lighting brackets and particularly to brackets provided with a convenience outlet.

One object of my invention is to provide a convenience outlet that shall be rigidly supported on the bracket.

Another object of my invention is to provide a convenience outlet on a bracket in which the supporting structure for the outlet shall be integral with the bracket.

Another object of my invention is to provide a convenience outlet for a bracket, in which the outlet shall consist of a minimum number of parts and be relatively simple in construction.

In brackets heretofore provided with a convenience outlet, the outlet consisted of a bayonet plug receptacle which was secured to the bracket by screws or bolts. In some brackets two parallel slots were disposed in the base of the bracket through which the bayonet blades were inserted to enter the registering recesses in the receptacle disposed behind the slots. In other brackets, the plug receptacle extended through an opening in the base of the bracket and was secured to the bracket by suitable means.

In the construction which I describe herein, the bracket is provided with two parallel slots extending through the base of the bracket.

Behind the slots on the rear surface of the bracket is disposed a partitioned porcelain box integral with the body of the bracket. The box is separated by the partition into two compartments, each of which contains a jaw contact member for receiving a corresponding blade contact of the bayonet plug. The walls of the box also support a shelf in each compartment upon which a terminal rests to permit proper connections between the wiring and the jaw contacts. By reason of the box construction being integral with the bracket body, a rigid support is provided thereby for the contact members of the convenience outlet.

The construction is illustrated in the accompanying drawings in which: Fig. 1 is a side elevational view of a bracket provided with a convenience outlet; Fig. 2 is a rear elevational view of the bracket in Fig. 1;

Fig. 3 is an elevational view of the lower portion of the bracket containing the convenience outlet terminals; Fig. 4 is a front elevational view of the supporting structure for the convenience outlet; Fig. 5 is a front elevational view of an assembled jaw contact member; Fig. 6 is a side elevational view of the contact shown in Fig. 5; Fig. 7 is a perspective view of an insulating cover; and Fig. 8 is a plan view of a spring clip therefor.

As illustrated in the accompanying drawings, a light bracket is provided with a base 2, a husk or receptacle 3 for supporting a socket for an electric light, and a convenience outlet 4 to which access may be had through two small openings 5 extending through the lower portion of the bracket base.

The convenience outlet consists of a porcelain box or support 6 divided into two compartments 7 and 8 by a partition 9. The inner wall surfaces of the two compartments are provided with horizontal ridges or shelves 10 and 11 upon which contact members or clips 13 are rigidly supported.

The porcelain box or support is integral with the porcelain base and thus provides a rigid structure for the convenience outlet. The partition serves to insulate the two contact members from each other and also to provide a support for the inner shelf portions upon which the contacts are secured.

The contacts or clips are provided to receive the blades of a plug. Engagement is made by inserting the blades through the openings 5 in the base of the bracket. In order to prevent the clips from becoming loose, they are tightly secured to the supporting shelves 10 and 11 by a bolt 14 and a nut 15 which tightens a washer 16 against the shelves as seats. A second nut 17 cooperates with the nut 15 to secure the tip of a wire connected to the conductors (not shown) provided for the lamp socket.

While the clip may be of any suitable design which will insure a tight sliding fit on the plug blade, the clip which I employ is provided with a bent portion 18 of substantially horse-shoe shape under stress, and

with tips 19 bent back upon themselves to engage each other with a yielding pressure. The blade when inserted is engaged by the tips.

5 After the clips are secured in position, a fiber cover 20 is placed about the front and sides of the porcelain box and locked in position by a small spring clip 21.

10 By means of the porcelain box, a more rigid structure is obtained for the convenience outlet and the contact clips may be more securely anchored in position. Better insulation is obtained since no extraneous metallic anchoring means are required as in other brackets 15 in which a socket is secured to the base. The bracket may be assembled with greater ease and has a minimum number of parts.

15 My invention is not limited, of course, to the specific construction or design illustrated 20 since modifications may be made therein without departing from the spirit and scope of the invention as set forth in the appended claims.

I claim as my invention:

25 1. As a new article of manufacture, a lighting bracket comprising a hollow shell of porcelain having an integral hollow support with a lateral opening through which contact members may be inserted, there being 30 openings through the shell communicating with the interior of the support, through which blades of a service plug are to be inserted, and projections on the interior of the support to engage the contact members and 35 retain them in position to be engaged by the blades on a service plug.

2. As a new article of manufacture, a lighting bracket comprising a hollow shell of porcelain having an integral support 40 with two chambers therein, each chamber having a lateral opening, there being an opening extending from each chamber through the shell, through which blades of a service plug are to be inserted, and projections on the interior of each chamber to 45 engage the contact members and retain them in position to be engaged by the blades on a service plug.

3. As a new article of manufacture, a wall 50 lighting bracket comprising a hollow shell of porcelain with an opening at the rear thereof, an integral support within the shell having two recesses in its rear face through which contact members may be inserted, there being 55 an opening extending through the shell from each recess, through which blades of a service plug are to be inserted, and projections in each recess to engage the contact members and retain them in position to be engaged by the blades on the service plug.

In testimony whereof, I have hereunto subscribed my name this 15th day of May, 1926.

JACOB DYM.
